UNITED STATES PATENT OFFICE.

ZYGMUNT LIPOWSKI, OF HOBOKEN, NEW JERSEY.

BOX-MAKING MACHINE.

1,279,730.

Specification of Letters Patent. Patented Sept. 24, 1918.

Application filed November 5, 1915. Serial No. 59,757.

To all whom it may concern:

Be it known that I, ZYGMUNT LIPOWSKI, a subject of Russia, and resident of Hoboken, in the county of Hudson and State 5 of New Jersey, have invented certain new and useful Improvements in Box-Making Machines, of which the following is a specification.

This invention relates to a box making 10 machine and comprises elements that automatically coact to form the cover or bottom of a box, and in this application will be designated as a box. The complete box is provided with what is termed a neck, the latter 15 is not shown or described in this application, and generally comprises a piece of cardboard which is fastened to the inner faces of the sides of the bottom of the box, the cover being hinged thereto.

Figure 1 represents in part a front elevation of the machine; Fig. 2 shows a top plan view of Fig. 1; Fig. 3 shows the remaining portion of the front elevation of the machine; Fig. 4 represents a right hand side 25 view of Fig. 3; Fig. 5 shows a top plan view of Fig. 3; Fig. 6 is an enlarged fragmentary portion of Fig. 1; Fig. 7 shows a top plan view of Fig. 6; Fig. 8 shows a section of Fig. 7 as on the line 8, 8; Fig. 9 represents an elevation of some of the details of Fig. 7; Fig. 30 10 shows an enlarged portion of Fig. 1; Fig. 11 is a right hand side view of Fig. 10; Fig. 12 shows a top plan view of Fig. 10; Fig. 13 shows an enlarged fragmentary portion of Fig. 10; Fig. 14 is a right hand side view of Fig. 13; Fig. 15 represents a top plan view of Fig. 13; Fig. 16 shows in part an enlarged section of Fig. 2 on the line 16, 16 and a side elevation of some of the details; Fig. 17 is an enlarged view of some details of Fig. 16; Fig. 18 represents a right hand side view of Fig. 17; Fig. 19 shows a top plan view of Fig. 17; Fig. 20 shows a top plan view of some of the details of Fig. 16; Fig. 21 shows a partial section as on the line 21, 21 of Fig. 7; Fig. 22 shows an enlarged side view of the shears of the machine; Fig. 23 is a left hand side view of Fig. 22; Fig. 24 shows a top plan view of Fig. 22; Fig. 25 represents a partial section of Fig. 22 on the line 25, 25; Fig. 26 shows a side elevation of a detail of Fig. 22; Fig. 27 is a top plan view of Fig. 26; Fig. 28 shows a section of Fig. 26 on the line 28, 28; Fig. 29 shows a side elevation of another detail of Fig. 22; Fig. 30 is a top plan view of Fig. 29; Fig. 31 is a section of Fig. 29 on the line 31, 31; Fig. 32 represents an enlarged view of a portion of Fig. 2 exemplifying a clamping and roller folding device; Fig. 33 shows an elevation 60 of Fig. 32 and part section of said figure on the line 33, 33; Fig. 34 represents in part a left hand side view of Fig. 33; Fig. 35 represents a left hand side view of some of the details of Fig. 33; Fig. 36 shows an enlarged 65 fragmentary view with a portion in axial section of another clamping and roller folding device of the machine; Fig. 37 represents a right hand side view and section of Fig. 36 on the line 37, 37; Fig. 38 shows a top plan 70 view of Fig. 36; Fig. 39 represents an enlarged fragmentary portion of Fig. 37; Fig. 40 is a section of Fig. 39 on the line 40, 40; Fig. 41 is a top plan view of a detail; Fig. 42 shows an enlarged portion of Fig. 1; Fig. 75 43 shows a top plan view of Fig. 42 with some additional details; Fig. 44 represents a right hand side view of Fig. 42; Fig. 45 shows a right hand side view of Fig. 43; Fig. 46 is a section of Fig. 42 on the line 46, 80 46; Fig. 47 shows a partial section of Fig. 44 on line 47, 47; Fig. 48 represents a right hand side view of some details of Fig. 16 representing a clamping, binding and roller folding device; Fig. 49 shows a right hand 85 side view of Fig. 48; Fig. 50 represents a top plan view of Fig. 48; Fig. 51 shows a section of Fig. 48 on the line 51, 51; Fig. 52 shows an enlarged fragmentary section of some details as on the line 16, 16 of Fig. 1; Fig. 53 90 shows an enlarged fragmentary portion of Fig. 2; Fig. 54 is an elevation of Fig. 53; Fig. 55 is a fragmentary right hand side view of Fig. 54 with a fragmentary portion of some details; Fig. 56 represents a partial 95 enlarged section as on the line 16, 16 of Fig. 2; Fig. 57 shows a top plan view of Fig. 56 when not sectioned; Fig. 58 is a partial section as on the line 58, 58 of Fig. 56; Fig. 59 is a left hand side view of a detail of Fig. 100 56; Fig. 60 is an enlarged portion of some details shown in Fig. 2; Fig. 61 represents an elevation of Fig. 60; Fig. 62 represents an inside plan view of the frame of the box made with the machine with its binder; Fig. 105 63 shows a bottom view of Fig. 62; Fig. 64 shows an enlarged end view of Fig. 62; Fig. 65 represents a plan view of the frame and binder partly in position with the head of cover looking toward the inside of the box; Fig. 66 shows a view similar to Fig. 65 with a further development in the manufacture 110

of the box; Fig. 67 is a rear view of Fig. 66; Fig. 68 shows a partial top view and section of Fig. 65 on the line 68, 68; Fig. 69 represents a rear view of the box completed; Fig. 5 70 is a top view of Fig. 69, Fig. 71 is an enlarged section through one of the corners of the box as on the line 71, 71 of Fig. 70; Fig. 72 shows a side view of a detail of Fig. 1 and Fig. 73 is an enlarged view of a detail of 10 Fig. 1.

In the description of the construction of the machine the different elements will be considered as closely as possible, in the order in which they perform their functions in 15 making the boxes.

The box, see Figs. 64 to 67, which is manufactured by the machine comprises the following parts, to wit: a box head 135, a box frame 136, with rectangular cross grooves 20 137. A duplex binder comprising the members 141 and 142, with the square ends 143 with the binder flap 144 extending from the member 142.

The ends 143 of the duplex binder indicate 25 where it has been completely severed by the blades of the shears to be described and the edge 155 of the flap 144 indicates where the duplex binder has been partially cut by the said shears.

30 Referring to Figs. 1 and 2, the table or platform 20 of the machine has formed therewith the front flange 21, rear flange 22, and side flanges 23 and 24. The table is supported at its four corners by means of the pair 35 of front legs 31, 32 and the pair of rear legs 33, 34. The legs 31 and 32 are connected by a cross brace 35 and the legs 33 and 34 are connected by a cross brace 36. A tie bolt 39 connects the cross braces 35 and 36.

40 A driving shaft 40 is journaled in the journal bearings 41, 42. A fly wheel 43 and a tight and loose pulley 44, 45 are provided for said shaft. The belt for said pulleys is not shown. A belt shifter comprises the 45 shifter bar 48 which is slidably supported in the brackets 49 and 50.

The shifter bar has fastened thereto a bracket 51. A cross shaft for the belt shifter is indicated at 55 and is supported in openings 50 in the flanges 21 and 22. An arm 56 has one end fastened to the cross shaft 55. A link 57 has one end pivoted to the swinging end of the arm 56 and the other end thereof is pivoted to the bracket 51.

55 Operating handles 58 are fastened to the ends of the cross shaft 55. The operator swings either one of the handles 58 and thereby the shifter bar 48 is moved to locate the belt either on the pulley 44 or 45. A 60 pinion 60 is fastened to the driving shaft 40. Journal bearings 61 and 62 are secured to the table 20 and have journaled thereon the intermediate shaft 63. The intermediate shaft 63 has fastened thereto the bevel gear 64, the pinion 65, and the spur gear 66. The

spur gear 66 meshes with the pinion 60. Journal bearings 70, 71 and 72 are secured upon the table 20 and have journaled thereon the main transmitting or rear shaft 73. A spur gear 75 and a number of other elements 70 to be described are fastened to said shaft. The spur gear 75 meshes with the pinion 65. By means of the train of gears just described the rotations of the driving shaft 40 which are in the direction of the arrow A, are 75 transmitted to the transmitting shaft 73, which latter is turned in the same direction.

Referring to Figs. 1, 2 and 42 to 47, attention is directed to the box head magazine indicated in its entirety by the numeral 80 78. The said magazine comprises the bottom runways 80, 81 which at the inlet end of the magazine are supported upon the cross brace 82, and at the discharging end are supported upon the angle bracket 83. A 85 pair of guides 84, 85 are fastened to the angle bracket 83. A pair of supporting strips 86, 87 are respectively fastened to said guides 84 and 85. A connecting plate 88 with the wing 89 is fastened to the top face of the 90 guides 84 and 85. Posts 92, 93 extend up from the cross brace 82 and each have a rabbit for the runways 80 and 81. Upper side bars 100 and lower side bars 101 connect the posts 92, 93 with the supporting strips 86, 95 and 87. A bracket 102 having the sleeve 103 with the spindle 104 supports bottom runways 80, 81 on one end. A pin 105 extending from the bracket 102 has journaled thereon the pulley 106. The bracket 83 has extending therefrom the sleeve 108 for the spindle 109. A lug 111 extends from the bracket 83. A pin 112 carried by the lug 111 has journaled thereon the pulley 113. Tubular brackets 115 on the table 20 support the spindles 104 and 109, so as to bring the connecting plate 88 of the said magazine 78 just below the lower surface of one of the receptacles of the turret to be described as shown clearly in Fig. 55. A separator 117 extends 110 from the post 93 and a guide rail 118 extends between the separator 117 and guide 84. A pusher slide 120 is movably supported upon the guide rail 118. The slide has extending from one side the lug 121 with perforations, 115 and has extending from its lower surface the lug 122 with perforations. A cross bar 123 extends from the slide 120 and has fastened thereto the pusher plate 125. To the leg 32 of the table 20 and adjacent to its 120 lower end is pivoted one end of a foot treadle 129 on a pivot 130. A cord 131 having one end fastened to the lug 121 extends over the pulley 106 and is fastened to the treadle 129. A cord 132 has one end fastened to 125 the lug 122, leads over the pulley 113 and has hanging therefrom the weight 134. A few box heads are indicated at 135, and which when the machine is in operation extend between the pusher plate 125 and the outlet 130.

end of the box head magazine. The cord 132 with its weight 134 cause the pusher plate 125 to force the box heads 135 toward the discharge end of the magazine. The treadle 129 with its appurtenances enables the pusher plate 125 to be moved to the inlet end of the magazine, so that the box heads 135 may be examined or added thereto. In the guides 84, 85 there is actuated a feed 10 slide. The feed slide comprises the plate 138, which is backed with the strengthening plate 139. Supporting fingers 140 are secured to the rear of plate 138 and extend above the same. On the transmitting shaft 15 73 is fastened a groove cam 145. To the lower face of the table 20 is fastened the bracket 146. A yoke 147 straddles the shaft 73 and has formed therewith the arm 148. A roller 149 is journaled on the yoke and engages the groove cam 145. A lever 150 is pivoted to the bracket 146 and has one end pinned to the arm 148. A link 151 has one end pinned to the strengthening plate 139 of the slide and the other end is pinned to the 25 lever 150. The box heads 135 are forced to and out of the discharging end of the magazine 78 by the pusher plate 125 and deposited upon the top edge of the plate 138 of the feed slide, and the latter is reciprocated by virtue of the rotations of the shaft 73 and the coaction of the grooved cam 145 and its appurtenances. The box heads 135 are forced into box frames of the turret as will be explained by the up strokes of the 30 slide having the plate 138. Fillers 153 are located in the guides 84 and 85 to prevent foreign substances from interfering with the reciprocations of the plate 138.

A turret is indicated in its entirety by the 40 numeral 160. It comprises the foot bracket 161 which is bolted to the table 20 and supports the column 162. A washer 163 preferably of fibrous material is supported upon the foot bracket 161. A turret head 164 with the inner cylindrical surface 165 has formed therewith the vertical sleeve 166 which is rotatably supported upon the column 162. Four horizontal sleeves 167 are formed with said head with their axial lines 45 so that those next adjacent make angles of ninety degrees with each other. A bevel gear 168 carrying the locking blocks 169 is fastened to the sleeve 166. With the head 164 are also formed the supplemental guide 50 sleeves 170 one of which is vertically above each horizontal sleeve 167. A washer 171 of fibrous material caps the column 162 and the head 164. A washer 172 is placed upon the washer 171. A nut 173 is in threaded 55 engagement with the top of the column 162. An oil cup 180 is supported on the column 162 above the nut 173 and discharges a lubricant into the spiral groove 181 on the outer surface of the column 162. Upon each 60 sleeve 167 is supported a receptacle 182

which comprises the main box portion having the side walls 183, 184, the bottom wall 185 and the sleeve 186. The sleeve 186 is fastened to the horizontal sleeve 167 by means of the screw 187. A cross slot 188 with the enlarged portions 189 is formed in the bottom wall 185. A cap 190 with the rectangular indentation 191 and the cavity 191^a, cross groove 192 and longitudinal slot 193 is secured to the receptacle by means of the screws 194. Vertical grooves 195 are formed in the side walls 183 and 184. Clamping plugs 196 each with a vertical slot 197 are located in openings formed in the side walls 183, 184. Springs 198 have 70 each one end fastened to the side walls 183, 184 by means of the screws 199 and the other end of each of the springs 198 has fastened thereto the plug 196. A pair of journal lugs 201 extend from the cap 190 and a latch lever 202 with the heel 203 at one end and the spring bearing end 204 at the other end is pivoted in said journal lugs 201. A spring 205 is located in the cavity 191^a and bears against the bearing end 204. A latch 85 210 with the heel 211 is located below the cap 190. Springs 213 and plungers 214 are located in the guide sleeves 170. The plungers 214 bear against the heels 211. A forming block 215 is slidably supported in 90 the box frame. The block 215 has formed in its roof the cavity 216 and has extending therefrom the plunger 217 that has pivoted thereto the roller 218.

To the sleeve 166 is fastened the bearing 100 collar 221 by means of the screws 222. A groove disk 223 with the cam groove 224 and sleeve 225 is supported upon the bearing collar 221 and registers with the cylindrical surface 165. The roller 218 engages the 105 groove 224.

The transmitting shaft 73 has fastened thereto the sector bevel gear 226. A journal bracket 227 is supported upon the table 20 and has journaled therein the shaft 228 110 which at one end carries the bevel gear 229 and at the other end the bevel gear 230. The bevel gear 230 meshes with the teeth of the sector gear 226 and the bevel gear 229 meshes with the gear 168. A grooved cam 115 231 is fastened to the shaft 73 and has coacting therewith a roller 232 which is carried on a yoke 233 that straddles the shaft 73. The yoke 233 has adjustably connected thereto the arm 234. A journal bearing 235 is supported upon the table 20 and has pivoted therein by means of the pivot 236 the arm 237, which in turn is pivoted to the arm 234 by means of the pin 238. A yoke 240 with the stem 241 is slidably supported in an 120 opening formed in the upper end of the arm 237. A block 242 with the vertical grooves 243 and an opening 244 is located in the yoke 240. Guide screws 245 in the yoke engage the grooves 243, so as to permit the 125 130 sleeve 167 to move vertically.

block to move vertically. A bracket 246 is fastened to the groove disk 223 and has formed therewith the pin 247 which engages the opening 244 of the block 242.

5 On the shaft 73 there is secured a groove cam 255. A yoke 256 is supported on the shaft 73 and carries a roller 257 that engages the groove of the cam 255. Journal brackets 258 are secured to the top of the 10 table 20 and have pivoted therein the shaft 259 which carries the arms 260 and 261. The yoke 256 is pinned to the arm 260 by means of a pivot bolt 262. Adjusting arms 263 are pinned to the arms 260 and 261 by 15 means of pivot bolts 264. Each of the adjusting arms 263 has adjustably connected thereto the adjusting spindle 265 that carries the locking foot 266. The spindles 265 are in threaded engagement with the arms 263 and are clamped in position by means 20 of the nuts 267.

The operations of the box head magazine 78 and the turret 160 are as follows: With the rotations of the shaft 73, the feed slide 25 having the plate 138 raises the box heads 135 from the magazine 78, carrying the said box heads upon the upper edge of the plate 138. The heads are held in proper position by means of the fingers 140. The plate 138 30 forces the box heads 135 through the cross slot 188 of the receptacle 182 and moves said heads slightly above the top edges of said slot. The enlarged portions 189 of the slot 188 provide clearances for the fingers 140. When the said box heads are in position in the receptacle 182, they are clamped 35 in position by being engaged by the grooves of the clamping plugs 196. After the said box heads 135 are in proper position in the 40 turret 160, the latter is turned through an angle of ninety degrees, by means of the rotation transmitted from the shaft 73 through the sector bevel gear 226, the bevel gears 229, 230 and 168. While the turret 45 160 is moving through its quadrant the shaft 73 is turning the cam 231 and thereby the arm 237 is swung, which causes the groove disk 223 to partially turn. The groove 224 coacting with the roller 218 50 moves the forming block 215 outwardly in the receptacle 182, and thereby the box head 135 is brought in proper position for the next operation in the formation of the box, when the turret 160 has finished the first 55 quadrant of its travel.

Referring to Figs. 1, 2, 6 to 9, 16 to 21, and 48 to 52, there is shown fastened to the table 20 the two side frames 274 and 275 by means of the screws 276. A front plate 60 277 with the feet 278 is secured to the side frames 274, 275 and is bolted to the table 20 by means of stud bolts 279. The front plate 277 has formed at its top the upper table 280 and the lower table 281. A central opening 282 and side openings 283 and

284 are formed in the front plate 277. Guide plates 289 and 290 are secured to the front plate 277. A vertical moving slide 291 with the pin 292 at its lower end and the horizontal guide 293 with the guide plates 294 and 295 is supported by the guide plates 289 and 290.

At one end of the plate 295 is fastened a bracket 296, to which is pivoted a tipping lever 297. An adjusting screw 298 in the bracket 296 adjusts the movements of the lever 297. At the other end of guide 293 is fastened the bracket 300, which carries the stop screw 301. A horizontal slide 305 is 75 slidably supported on the guide 293. A vertical bracket 306 with the stationary member 307 of a pair of grippers formed with said bracket is fastened to the horizontal slide 305. A movable member 308 of 80 said grippers is pivoted to the bracket 306 85 by means of a pivot 309. An arm with the legs 310 and 311 is formed with the movable member 308. A foot 312 is formed with the leg 310. A spring 320 connects the leg 311 with the slide 305. The slide 305 has extending therefrom a pin 321 to which latter is connected one end of a connecting rod as will be explained and by virtue of which the said slide 305 is reciprocated. From the rear face of the slide 291 extend a pair of 90 slotted pins 322 that each carry a pivot 323. A pin 324 extends from the slide 291 and carries the cam 325, which latter is held in position by the nut 326. A pair of trippers each with the arms 327 and 328 are pivoted 95 to the front plate 277 by means of pins 329. The cam 325 is in the path of the arms 327 of the said trippers. A pair of slotted pins 331 each with a pivot 332 are fastened to the rear face of the front plate 277. A 100 folding frame 333 comprises the folding plate 334, the vertical members 335 with the cam openings 336 at their top ends and the guide openings 337 at their lower ends. The cam openings 336 engage the pivots 323 105 and the guide openings 337 engage the pivots 322. 110

A brace 344 connects the vertical members 335 of the folding frame 333, and a spring 345 connects the brace 344 with the front 115 plate 277. With the reciprocations of the slide 305 the grippers with the movable members 308 is opened and closed. The movable member 308 is opened when the leg 311 contacts with the stop screw 301, and 120 closes by gravity with the weight of the leg 310, when the slide 305 moves from the said stop screw. When the slide 305 reaches the other end of its stroke the foot 312 of the arm 310 strikes the lever 297, 125 opens the member 308 and trips over said lever 297. Upon the return stroke of the slide 305 the foot 312 swings the lever 297 out of the way, and the movable member 308 of the grippers remains closed. With 130

the vertical reciprocations of the slide 291 the folding frame 333 is operated to raise and swing from the lower table 281 to the upper table 280. The frame 333 is actuated by virtue of the cam 325 separating the arms 327 of the trippers, by virtue of which the arms 328 raise the folding plate 334. While the plate 334 is rising the cam openings 336 coacting with the pivots 323, swing 10 the said plate 334 forwardly from the table 281 to the table 280. When the cam 325 is released from the arms 327 the latter lower by gravity, and the tension of the spring 345 causes the folding frame 333 to 15 move to its lower position.

The folding frame 333 by virtue of its movements folds over the inner edge of a binder on a frame of the box as will be fully explained.

20 Vertical side frames 350 and 351 are bolted to the side frames 274 and 275 respectively. The side frame 350 has formed therewith the journal boss 352 and the side frame 351 has formed therewith the journal boss 353.

25 A frame extension 354 with the journal boss 355 is bolted to the frame 350, and a frame extension 356 with the journal boss 357 is bolted to the frame 351. To the front face of the frames 350 and 351 is 30 fastened the annular front frame 360, and with the latter is formed the upper boss 361 and the lower boss 362. To the rear face of the frames 350 and 351 is fastened the annular rear frame 363 which has formed 35 therewith the vertical guides 364. In the boss 362 is slidably guided a sleeve 367 which has formed at its upper end the cylindrical cross head 368. A plunger rod 369 is shown with the enlarged portion 370 at its lower 40 end, and the spindle 371 at its upper end.

The plunger rod 369 is guided in the sleeve 367, the portion 370 is guided in the boss 362 and the spindle 371 is guided in the boss 361. A spring 372 in the sleeve 367 encircles 45 the spindle 371 and bears between the upper face of the plunger rod 369 and the upper portion of said sleeve 367. A clamping ring 378 is clamped to the spindle 371 above the cross-head 368. A clamping bracket 379 50 is fastened to the spindle 371 above the boss 361 and has extending therefrom a guide pin 380 which engages an opening in a boss 381 formed with the front frame 360. A presser bar 382 is pinned to the enlarged portion 370 of the plunger 369. A shaft 385 is supported in the journal bosses 352, 353 55 and has fastened thereto the arm 386 which engages the cross-head 368. An arm 387 is fastened to the shaft 385. A connecting rod 60 388 has one end pinned to the arm 387. A journal bearing 389 is fastened to the table 20. A grooved cam 390 is fastened to the shaft 73. A walking beam 391 is pivoted by means of a pin 392 to the journal bearing 389. One end of the walking beam 391

has journaled thereon a roller 393 which engages the groove of the cam 390. The other end of the beam is pinned to the connecting rod 388 by means of the pin 394.

The presser bar 382 receives its movements from the shaft 73 through the interposed mechanism comprising the cam 390, causing the walking beam 391, the connecting rod 388, the arm 387 and the shaft 385 to oscillate. The arm 386 is caused to oscillate by the shaft 385, and thereby the sleeve 367 is vertically reciprocated. The spring 372 forces the plunger rod 369 down the sleeve 367, until the clamping ring 378 bears upon the top face of the cross-head 368. 80 Thereby is secured an easy and pliable means for operating the presser bar 382. The guide pin 380 by its coaction with the guide opening in the boss 381 maintains the presser bar 382 in proper alignment.

85 The presser bar secures the binder and frame of the box manufactured upon the table 280 at the proper time as will be fully explained.

In the guides 364 of the frame 363 is adjustably fastened the guide bracket 405 by means of the bolts 406. The bracket 405 has formed therein the vertical guide opening 407. A sleeve 408 with the head 409 is located in the opening 407. A hinge lug 410 is formed with said head 409, and the latter has recesses 411 formed in its sides. A spindle 412 with the shouldered portion 413 and foot end 415 is slidably located in the head 409. A clamping foot 448 is pivoted to the foot end 415. A spring 419 bears between the upper end of the sleeve 408 and the shoulder portion 413 of the spindle 412. A guide plate 420 is fastened to the head 409 and is guided in a guide opening 421 formed in the bracket 405. 100

A cap 423 with an elongated opening 424 is bolted to the guide plate 420 over a similar opening in the latter.

105 A finger 425 is slidably located in a guide opening 426 formed in the guide plate 420. A spring 427 extends between the top of the finger 425 and the top of the guide opening 426. A latch pin 430 extends from the finger 425 and passes through the elongated opening 424. A hinge bracket 431 extends from the guide plate 420 and has pivoted therein the latch lever 432 having the heel end 433 and an opening 434 in its upper end.

110 A bracket 435 with the guide clamping pin 435 is clamped to the spindle 412 and has formed therein an opening 436 with a cavity 437. A spring 438 with a plunger 439 is located in said opening and cavity and bears against said latch lever 432. An arm 440 115 is hinged to the hinge lug 410 and has pivoted to its lower end the roller frame with the arms 441. A roller 442 is pivoted in the arms 441. A lug 443 has journaled therein the guide roller 445. A spring 446 120

125 is pivoted to its lower end the roller frame with the arms 441. A roller 442 is pivoted in the arms 441. A lug 443 has journaled therein the guide roller 445. A spring 446 130

with the cam 447 has one end fastened to the rear frame 363. A bolt 448 is in threaded engagement with the frame 363 and is encircled with the helical spring 449. The bolt 448 extends through an opening in the lower end of the spring 446. The cam 447 is in the path of the guide roller 445, and by reason thereof the said guide roller 445 during its movement is forced against the 10 box head 185, that is held upon the outer face of the forming block 215 as will be further explained. The clamping foot 418 is in vertical alinement with the top face of the forming block 215 when it extends out 15 of the receptacle 182, and bears upon the frame 136 with the binder 141, 142 of the box that is being manufactured. The finger 425 is in vertical alinement with the opening 191 in the cap 190 so as to bend down a portion of the binder 142 of the box that 20 is being made. A shaft 451 is journaled in the boss 355 of the frame 354 and in the boss 357 of the frame 356. An arm 452 with the forked end 453 has one end fastened to the 25 shaft 451. The forked end 453 engages the recess 411 of the head 409.

A screw 454 is in threaded engagement with the frame 360 and has formed therewith the sleeve 456. A cylindrical cross-head 457 encircles the sleeve 456 and has formed therewith the flange 458. A plunger 459 is secured to the cross-head 457 by means of the screw 460. A spindle 461 is formed with the plunger 459. A spring 462 is located in the sleeve 456, encircles the spindle 461 and bears between the head end of the sleeve 456 and the shoulder between the spindle 461 and the plunger 459. A clamping plate 463 is fastened to the plunger 459 and a guide pin 464 extends from the said clamping plate. The plunger 459 is slidably guided in the opening 468 of the boss 469 of the frame 363, and the guide pin 464 registers with an opening in said boss. 40 An arm 465 has one end fastened to the shaft 385 and its forked end 466 engages the cross head 457. With the oscillations of the shaft 385 the cross head 457 is pulled from the forming block 215. The spring 462 reverses the movement of the plunger 459. 45 An arm 465 has one end fastened to the shaft 385 and its forked end 466 engages the cross head 457. With the oscillations of the shaft 385 the cross head 457 is pulled from the forming block 215. The spring 462 reverses the movement of the plunger 459.

The shaft 451 has fastened to one end thereof the arm 470 from which extends the separator 471. A connecting rod 472 has one end supported on a pivot bolt 473 which is secured in the separator 471. The lower end of the connecting rod 472 is pinned to the walking beam 473 by means of the pivot bolt 475. The walking beam is 55 supported on the pin 392 and has journaled thereto the roller 476. A groove cam 477 is fastened to the shaft 73 and its groove engages the roller 476.

With the rotations of the shaft 73 the 60 shaft 451 is oscillated through the inter-

vention of the cam 477, the walking beam 473, connecting rod 472 and the arm 470. With the oscillations of the shaft 451 the arm 452 is oscillated. The head 409 is reciprocated with the oscillations of the arm 452. With the downward stroke of the head 409 the shouldered portion 413 of the spindle 412 is forced down through the intervention of the spring 419. This forces the clamping foot 418 upon the frame 136 and binder 141 142 of the box being manufactured upon the top face of the forming block 215. The guide plate 420 moves down with the head 409, and the finger 425 through the tension of the spring 427 is moved down with the guide plate 420. The bracket 435 moves down with the spindle 412. When the clamping foot 418 bottoms or reaches the end of its downward stroke, the head 409 through the compression of the spring 419 allows the head 409 to move farther downwardly a small distance, and the finger 425 enters the opening 191 in the cap 190 and bends the flap 144 of the box over its recess 411 as will be described.

When the head 409 moves down while the spindle 412 remains at rest the pin 435 of the bracket 435 travels up in its opening 434, and disengages the heel end 433 from the pin 430, and the tension of the spring 427 pulls up the finger 425. At the instant that the finger 425 has completed its downward stroke, the lower edge of the guide plate 420 strikes the latch lever 202 and disengages the heel 203 from the heel 211 of the latch 210, and the latter by means of plunger 214 shoots outwardly and bends the binder 142 under the frame 136 of the box. When the head 409 is again moved upwardly the said head contacts again with the bracket 435, and the elements are brought in the positions shown particularly in Fig. 51. When the head 409 is descending the roller 442 is rolled downwardly and bends the binder 141 over the top portion of the box 110 head 135.

Referring to Figs. 1, 2, 16 and 36 to 41, attention is directed to a clamping and roller folding element designated in its entirety by the numeral 480. The said device 115 comprises a guide barrel 482 having the guide face 483 which is bolted to the table 20 by means of the bolts 484.

A sleeve 485 with the large internal diameter 486 and small internal diameter 487 120 is located in the barrel 482. The said sleeve is threaded at its lower end 488.

An angle bracket with the horizontal member 489, vertical member 490 and apron 491 is secured to the top end of the sleeve 125 485. An arm 492 is hinged to the apron 491 and carries the roller frame 493, and in the latter is journaled the folding roller 495. A pin 496 with the head 497 extends from the apron 491 and passes through the 130

arm 492. A spring 498 is interposed between the head 497 and the arm 492. An adjustable stop bolt 500 is in threaded engagement with the arm 492 and is clamped to the latter by means of the clamping nut 501. A plunger 502 with the enlarged portion 503 is slidably located in the sleeve 485. A spring 504 is located in the sleeve 485 and bears against the enlarged portion 503 of the plunger 502.

A bracket 509 is fastened to the upper end of said enlarged portion 503 and has pivoted thereto the guide arms 510 by means of the pivot bolts 511. Each of the arms 510 has formed therein vertical guide openings 512, that curve downwardly to the axial center of the plunger 502 as indicated at the curved positions 513. A horizontal table 514 is formed with the bracket 509. Guide flanges 515 extend from the arms 510. Bending and clamping bars are indicated at 520 and have extending therefrom the supporting bolts 521, that pass through openings in the said flanges 515. Springs 522 encircle the bolts 521 and bear between the bars 520 and the flanges 515. Bending and clamping fingers 523 are pivoted to the upper end of the arms 510 and have each formed therewith the forked hinge end 524. To each hinge end 524 there is pivoted a plunger 525 by means of the pivot screws 526.

A pin 527 is formed with each plunger 525. A barrel 531 with the vertical slots 532 and the eye end 533 encircles each plunger 525. A spring 534 is located in the barrel 531, encircles the pin 527 and bears against the plunger 525. A guide pin 535 extends through each plunger 525 and engages the slots 532. A screw pivot 536 is in threaded engagement with each vertical member 490, and extends through its accompanying arm 510 and eye end 533. A washer 537 is held in position on the pivot 536 by means of the pin 538. A roller 539 is carried on the pivot 536 in the opening in the arm 510, of the pin 538. A flange collar 540 is in threaded engagement with the threaded end 488 of the sleeve 485. A nut 541 locks the flanged collar 540 in position. A nut 542 is carried by the plunger 502. To the lower face of the table 20 is fastened a bracket 545 in which is supported an oscillating pin 546. An arm 547 has formed therewith the forked end 548. One end of the arm 547 is fastened to the pin 546 and its forked end 548 engages the collar 540.

The clamping and roller folding device 480 operates in connection with the clamping foot 418 and its immediate coacting elements. The pin 546 is oscillated by means which will be described. Thereby the arm 547 is swung at the proper times and by which the sleeve 485 is reciprocated. Referring particularly to Figs. 36 to 41 the device 480 is shown in its closed position with

the box partly formed. The box-head 135, is indicated with its frame 136 and the binder 141, 142. The top and bottom portions of the binder with respect to the box head are supposed to have been folded respectively by the rollers 442 and 495. From the position of the elements as shown, particularly in Fig. 36 to detach the box from the device 480, the arm 547 swings down, which pulls down the sleeve 485, and the tension of the spring 504 will prevent the plunger 502 from at first descending. This will cause the rollers 539 to descend in the guide openings 512, and thereby the barrels 531 are lowered. The lowering of the barrels 531 cause the binding and clamping fingers 525 to open and swing in the direction of the arrows 523^a. When the rollers 539 reach the curved portions 513, then the guide arms 510 swing open in the same directions as indicated by the said arrows 523^a.

By this means the bending and clamping bars 520 are disengaged from the box that is being manufactured. Next by the continued downward movement of the sleeve 485, the bracket 509 is lowered against the tension of the spring 504 and the table 514 is lowered from the box. The device 480 is now ready for its reverse operations, and which briefly stated are as follows: When the sleeve 485 rises and before it has reached its topmost position the frame 136 with its binder 141, 142 has been located upon the table 514 as will be explained, and by the tension of the spring 504 the frame 136 and binder 141, 142 are clamped against the lower face of the forming block 215. The guide arms 510 are swung up and thereby the bending and clamping bars 520 bend and clamp the frame 136 and binder against the side faces of the forming block 215. Next the fingers 523 swing down, bend and clamp the frame 136 and binder 141, 142 against the top face of the forming block 215 and top edge of the box heads 135. Then the roller 495 folds the lower portion of the binder upon the outside face of said box head 135.

Referring to Figs. 1 to 5 attention is directed to the gluing appurtenances of the machine. A platform 555 with the opening 556 has one end bolted to the cross-brace 35. A column 561 has secured thereto the other end of the platform 555 by means of screws 562. A second platform 563 is fastened to the column 561. An arm 564 with the boss 565 is formed with the column 561 and an arm 566 with a journal bearing 567 is formed with said column. A grooved pulley 568 is journaled to the column 561.

A journal bracket 570 is bolted to the table 20, and a shaft 571 is journaled in the bracket 570 and the journal bearing 567. A pulley 572 is fastened to the shaft 571. A pulley 573 is fastened to the driving shaft 130.

40, and a belt 574 connects the pulleys 572 and 573 so that rotation is transmitted from the driving shaft 40 to the shaft 571. A driving wheel with a flexible disk 575 is adjustably fastened to the shaft 571, by means of the screw 576.

An arm 577 with the journal hinge 578 and the journal sleeve 579 is hinged to the boss 565, by means of the hinge bolt 580. A spindle 581 is journaled in the journal sleeve 579 and at one end has fastened thereto the spur gear 582 and at the other end the presser wheel 583. To the arm 577 is fastened the separator bracket 584 to guide the duplex binder 141, 142 as will be explained.

In the arm 564 is formed the journal bearing 590 and a bracket 591 with the journal bearing 592 is formed with the arm 564. A shaft 593 is slidably journaled in the bearings 590 and 592. A spur gear 594, grooved pulley 595 and disk wheel 596 are fastened to one end of the shaft 593, and a presser drum 597 are fastened to the said shaft 593. A spring 598 with the spring caps 599 and 600 are located in the bearing 592. An adjusting screw 601 is in threaded engagement with the outer wall of the bearing 592 and bears against the cap 600. The said screw is clamped in position by the nut 602. The cap 599 bears against the end of the shaft 593. With the elements just described means are provided to obtain contact between the disk wheel 596 and the flexible disk 575. A bracket 603 is fastened to the arm 564 and has extending therefrom the pins 606, 607 and 608. A pair of guide disks 609 are adjustably fastened to the pin 606, a pair of guide disks 610 are adjustably fastened to the pin 608 and a similar pair of guide disks 611 are adjustably fastened to the pin 607.

Upon the platform 555 is supported a frame comprising the members 616 and 617 which are connected by the angle iron 618 and the connecting plate 619. From the members 616 and 617 extend pivots 620 that each have hinged thereon one end of an arm 621. Lugs 622 extend from each of the members 616 and 617. An adjusting screw 623 is in threaded engagement with the arm 621 and abuts upon the lug 622. A clamping nut 624 maintains the screw 623 in locked position. A shaft 625 is journaled in bearings extending from the upper faces of the arms 621. A presser drum 626 is fastened to the shaft 625. Pivots 630 extend from the members 616 and 617, and have each hinged thereto one end of an arm 631 which latter has a slot 632 at its outer end. The arm 631 has formed therewith a cap 633 which co-acts with a bearing 634 formed in its accompanying member of the frame.

A screw 635 is pivoted to each of the members 616 and 617 and extends through the slot 632 of its accompanying arm 631.

65 A clamping nut 636 on the screw 635 locks

the arm 631 in proper position. A shaft 638 is journaled in the bearings 634 and has fastened thereto the gluing drum 639 and the grooved pulley 640. A pin 641 extends from the member 616 of the frame and has journaled thereon the guide roller 642. A pin 643 extends from the frame 616 and has journaled thereon the guide roller 644. A glue pot is shown comprising the upper member 648 and the lower member 649 which forms a compartment 650 for water. A steam discharge nozzle 651 is formed with the member 648.

The glue pot is supported at one end upon the angle 618 and at the other end upon an angle 652 extending from the table 650. A gas burner 657 is located upon the platform 555. A bracket 660 with the arms 661 and 662 extends from the platform 555. A reel 663 for the binder strip 142 is journaled to the arm 661 and a reel 664 is journaled to the arm 662 for the binder strip 141. Upon the platform 563 are located appurtenances similar to those described upon the platform 555 a few of which will be indicated by the same numerals. The gluing drum in this instance is indicated at 670, the pressure drum by 671 and the grooved pulley by 672. A belt 675 is indicated leading from the grooved pulley 595 to the under side of the grooved pulley 640, then over the pulley 568, under the pulley 672 and from the latter returns to the pulley 595.

The operations of the gluing device are as follows: The rotations of the shaft 571 are transmitted through the driving wheel having the disk 575 to the disk wheel 596. The rotations of the disk wheel 596 are varied by locating the driving wheel having the disk 575 at different distances from the center of the shaft 593. With the rotations of the shaft 593, the rotations of the grooved pulley 595, by means of the belt 675, are transmitted to the pulleys 640 and 672. The idler pulley 568 can be clamped in different positions in the slot 569 in the columns 561 and thereby adjust the tension of the belt 675.

The reel 663 carries a binder strip 142 and the reel 664 carries a binder strip 141. The binder strip 142 is led over the spindle 645 between the guide disks 646 of the frame on the platform 555. The binder strip 142 then passes under the guide roller 642, then over the upper drum 626. From the latter drum the strip 142 leads under the guide roller 644, thence around the pins 607 and 606, then between the presser drum 597 and presser wheel 583.

The reel 664 carries a second binder strip 141, and its course in the frame on the platform 563 is as follows. The binder strip is led over the spindle 645 between the guide disks 646. The binder strip 141 then passes over the guide roller 642, thence over the upper drum 671. From the latter the binder

strip 141 leads under the guide roller 644, thence around the pins 608 and 606, then between the presser drum 597 and presser wheel 583. The gluing drums 639 and 670 of the frames on each of the platforms 555 and 563 carry glue that is contained in the upper members 648 of the glue pots to the upper drums 626 and 671. The latter covers the inside face of each of the binder strips 10 with glue, and said strips are respectively independently driven to pins 607 and 608. The pair of disks 611 and the pair of disks 610 are each located and spaced to permit its respective binder strip to pass therethrough, 15 so that the strips 141, 142 will be led to the pin 606 slightly overlapping each other. This is accompanied by locating the pairs of guide disks 610 and 611 not in line with each other but one pair somewhat to one side 20 from a vertical plane passing through the drum 597 and the other pair of guide disks somewhat to the other side of said vertical plane (see Fig. 4). The guide disks 609 are located centrally with respect to said plane 25 and are distant from each other so that the adjoining edges of the strip 141 and 142 will overlap each other when they pass between the drum 597 and the wheel 583, and are thereby glued to each other ready for the 30 next operation. The gas burners 659 maintain the glue of the proper consistency.

Referring to Figs. 1, 2 and 10 to 15, attention is directed to the box frame magazine. The magazine comprises a frame with 35 the top member 685 and the legs 686, 687. A block 688 with a groove 689 is formed with the top member 685 and a cap 690 is secured to the block 688. The top member 685 has formed therewith the horizontal leg 691. A 40 movable guide column 694 has formed therewith a vertical guide groove 695 and is adjustably fastened to the block 688 by means of the bolt 696. A stationary guide column 698 with the guide groove 699 is fastened to 45 the leg 691 by means of the bolt 700. The legs 686 and 687 are bolted to the table 20 by means of the bolts 701, 702. A table 703 with a guide slot 704 is fastened to said block 688. The said table is slightly separated from and below the lower faces of the 50 guide columns 694 and 698. One end of said table 703 has fastened thereto a thin leg 705, which is fastened to the upper portion of the top member 685. A cross head 706 reciprocates in the slot 704 and has pinned thereto one end of a link 707 by means of a pin 708.

A journal bearing 714 is formed with the leg 686. A journal bracket 715 is fastened to the table 20, and a shaft 716 is journaled 55 in the journal bracket 715 and in the bearing 714. A grooved cam 717 is fastened to the shaft 73. An arm 718 on one end of the shaft 716 has journaled thereon a roller 719, which engages the groove of the cam 717. 60 The other end of the shaft 716 has formed

therewith the tapered end 720 with the threaded end 721. An arm with the members 722, 723 is hinged on the tapered end 720 and is held in position by the nut 724. The upper end of the arm with the members 70 722, 723 is pinned by means of the pin 725 to the link 707. A pusher comprising the lower plate 726 and the upper plate 727 extends from the cross-head 706 and slides upon the table 703 below the bevel of the 75 lower faces of the columns 694 and 698. With the leg 687 is formed a guide with the guide plates 730 and 731.

A slide 735 is guided by the guide plate 730 and 731. A cross plate 736 is fastened 80 to the slide 735 having the projecting pins 737, 738. A screw 739 with a right handed and left handed thread is fastened to the cross plate 736. Flanged guide bosses 740 and 741 are in threaded engagement with 85 the screw 739. A nut 742 locks the boss 740 in position and a spring 743 on the screw 739 maintains the boss 741 in position. An angle table 745 is carried by the cross plate 736 and in turn adjustably supports the 90 guide angles 746, 747. The said angles have elongated openings 748 through which pass the clamping screws 750, by which the said guide angles are clamped in place. A guide bracket 751 is fastened to the column 698 95 and has formed therewith the lower flaring face 752. To the top member 685 is pivoted one end of the guide frame 755 by means of the pivot screw 756.

The frame 755 has formed therewith the 100 guide arms 757 which straddle the bracket 751. A locking lever 764, with the heel 765 is pivoted to the top member 685 below the guide frame 755, by means of the pin 766. By swinging the lever 764 in the direction 105 of the arrow B the heel 765 is brought to bear against the frame 755 and the latter is prevented from lowering. A bracket 770 extends from the slide 735. The latter bracket by coacting with the appurtenances of a 110 pair of shears to be described adjusts the level of the table 745 as will be described. A spring 771 has one end fastened to a screw 772 extending from the leg 687 and its other end is fastened to the pin 737. A locking 115 lever 773 with the heel 774 has one end pinned to the leg 687 and the heel 774 can be located below the pin 738, to maintain the slide 735 in a lowered position.

In the guide columns 694 and 698 of the 120 frame magazine are located one over the other a plurality of box frames 136. A follower weight 775 is fitted in said guides to secure the proper feeding of said frames from said guide columns.

Referring to Figs. 1, 2, 3, 5, and 72. A split bracket 780 with the ears 781 is fastened to the tie bolt 39. A stanchion 782 is clamped in the barrel 783 of said bracket. A second split bracket with the barrel 784 and 130

- split ears 785 is fastened to the stanchion 782. A guide pin 786 is clamped in the said second split bracket. Guide disks 787 are adjustably fastened to the guide pin 786.
- 5 To the cross brace 36 is fastened a split bracket 789 having ears 790 and the latter are clamped by means of a screw 791.
- A rod 795 is clamped by the ears 790. A column 796 is carried by the rod 795. The 10 latter is split at its upper end and clamps a pivot 797 to which latter is journaled a flanged guide roller 798. A bracket 799 is fastened to the table 20 and has extending therefrom a pivot 800 and on the latter is 15 journaled a flanged guide roller 801. To the leg 31 of the table 20 is fastened a bracket 802 in which is fastened a guide pin 803 with the guide disks 804.

The operation of the frame magazine with 20 its connecting elements as just described are as follows:

- The duplex binder 141, 142, leads from between the presser wheel 583 and presser drum 597 to the guide pin 803 between the 25 guide disks 804. The duplex binder is then led over the guide pin 786 between the guide disks 787 and from thence under the flanged guide roller 798. The binder next is led over the flanged guide roller 801, and passes 30 between the arm having the members 722 and 723. Next the binder is led over the flanged guide bosses 740 and 741 and passes over the angle table 745, below the flaring face 752 of the bracket 751 between the guide arms 35 757. In the guides 694 and 698 are located a plurality of box frames 136, the lower one of which bears upon the table 703 and the lower plate 726 of the pusher. With the rotations of the shaft 73 and the intervening elements the shaft 716 is oscillated, which in turn oscillates the arm with the member 722 and 723. Thereby the pusher having the plates 726 and 727 is reciprocated and the lowermost box frame 136 is 40 moved, so that one of its ends extends somewhat beyond the angle table 745 and is located upon the duplex binder 141, 142. Upon the return stroke of the cross-head 706 the latter is located in the position clearly shown 45 50 in Figs. 1 and 10 for another operation.

Referring to Figs. 1, 2, 6, 8 and 16, journal brackets 812 and 813 are bolted to the table 20 and have journaled therein the cross shaft 814 which at one end has fastened thereto 55 the bevel gear 815 that meshes with the bevel gear 64. A grooved cam 816 is fastened to the shaft 814. A yoke 818 straddles the shaft 814 and carries a roller 819 which engages the groove of the cam 816. An arm 60 820 has one end fastened to the oscillating pin 546 and the other end thereof is pinned to the yoke 818 by means of the pin 821. By this means the pin 546 is oscillated when the shaft 73 turns.

Over the table 20 is supported a stationary groove cam disk 828 by means of the legs 829. The disk 828 has formed therein the cam groove 831. A rotary disk 832 has a boss 833 which extends through the disk 828 and is fastened to the shaft 814. 65 70

Guides 835 on the disk 832 hold a slide 836 having an elongated opening 838 and which can be clamped in different positions by means of the pin 839 and the clamping nut 840. A roller 842 is journaled on the 75 pin 839 which engages the groove 831.

An adjustable connecting rod 845 has one end supported on the pin 321 and the other end is pinned to the slide 836 by means of the pin 846. With the rotations of the shaft 80 73 the cross shaft 814 is rotated and thereby the rotary disk 832 is rotated. With the rotations of the latter the roller 842 rolls in the cam groove 831 and the slide 836 moves in its guide through the coaction of 85 the roller 842 and through the intervention of the connecting rod 845 the horizontal slide 305 is reciprocated. When the slide 305 is at the end of its stroke opposite to that shown particularly in Figs. 1 and 6, it 90 grips the duplex binder and the box frame which has been moved by the plate 727 of the pusher and locates the same upon the upper table 280, when said slide returns to the position shown in Figs. 1 and 6. 95

Referring to Figs. 1, 2, 6, 22 to 25 and 60, 61 attention is directed to the shears of the machine and its coating elements.

Upon the table 20 is bolted the bracket 855 at the upper end of which is the slide 100 guide 856 with the guide plates 857 and 858. In the plate 857 is formed a guide opening 860 with the curved end 861, and in the plate 858 is formed the guide opening 862 with the curved end 863. A slide 864 is 105 located in the slide guide 856. A boss 865 extends from the bracket 855 and has pivoted thereto one end of the arm 866 by means of the pivot screw 867. A slot 868 is formed in the upper end of the arm 866. A boss 871 is 110 located from the slide 864 and has extending therefrom the pivot screw 872 which engages the slot 868 of the arm 866. A pivot 873, shouldered at 874 with the hexagonal head 875 is in threaded engagement with the slide 864. 115

A thimble 876 with the collar 877 with the shouldered portion 878 encircles the pivot 873. An upper blade 879 with the long cutting edge 880 and the rear arm 881 is pivoted on the pivot 873. The arm 881 has extending therefrom the pivot 882 that engages the guide opening 862. A second upper blade 883 with the short cutting edge 884 has formed therewith the curved guide arm 885. A separator bracket 887 is located between the blades 879 and 883 and screws 888 connect the blades 879, 883 and the sepa-

rator bracket 887. On the pivot 873 is pivoted the inner lower blade 894 with the loose cutting edge 895 and the arm 896. A pivot 897 extends from the arm 896 which 5 engages the guide opening 860. The long cutting edge 895 coacts with the long cutting edge 880 of the blade 879. A second lower short cutting blade 898 with the cutting edge 899 is pivoted on the thimble 876 10 and coacts with the short cutting edge 884 of the blade 883.

A spring 906 bears between the shouldered portion 877 of the thimble 875 and the shouldered portion 874 of the pivot 873 to 15 force the thimble 876 against the blade 894. A spring 907 bears between the blades 894 and 898. A pivot screw 908 is in threaded engagement with arm 896 of the blade 894 and extends through the blade 898. A 20 spring 909 encircles the pivot screw 908 and bears between the blades 894 and 898.

To the shaft 73 is fastened a groove cam 914 with the groove 915. A yoke 916 straddles the shaft 73 and has journaled thereon 25 a roller 917 that engages the groove 915. A bar 919 has one end fastened to the yoke 916. Journal brackets 920 and 921 are bolted to the table 20 and have journaled therein the cross shaft 922. Arms 923 and 924 30 are fastened to the shaft 922. A bolt 925 connects the arm 923 and the bar 919. A link 926 has one end pinned to the arm 866 by means of the screw 927 and the other end of said link is pinned to the arm 924 by 35 means of the bolt 930. A stanchion 936 extends up from the table 20 and has fastened thereto one end of a spring 937, the other end of which latter is fastened to the bolt 925. A trigger 938 with arms 939 and 940 40 is pivoted to the link 926 by means of the pivot 941. The lower edge of the trigger is in the path of the bracket 770 of the slide 735. The trigger 938 bears upon the top edge of the bracket 770 when the arm 866 is 45 in the position indicated in Figs. 22 and 61, and when the blades of the shears are in their open position, and by virtue of which the angle table 745 is lowered somewhat to allow the duplex binder 141, 142 and the 50 frame 136 to be easily pulled by the grippers having the stationary member 307 and the movable member 308 upon the upper table 280.

To operate the shears the rotations of the 55 shaft 73 turns the groove cam 914, by virtue of which the bar 919 is reciprocated. Thereby the arm 866 is oscillated and the slide 864 is reciprocated. When the elements are in the position shown particularly 60 in Fig. 22 the blades of the double shears are open and the duplex binder 141, 142 and frame 136 are located with respect to said shears in the position shown in said Fig. 22. When the arm 866 moves in the

direction of the arrow C and the pivot 882 65 enters the curved end 863 and the pivot 897 enters the curved end 861, the shears will close and sever the duplex binder, by means of the long cutting blades 880 and 895, and will also cut in said binder a short slot by 70 means of the cutting blades 884 and 899, as will be fully explained further on. The shears open when the arm 866 has returned to the position shown in Fig. 22.

Referring to Figs. 1 and 2 journal brackets 951 and 952 are bolted to the lower face of table 20 and have journaled thereon the cross shaft 953. An arm 954 has one end fastened to the shaft 953 and extends through an opening 955 in the table 20 and has connected to its swinging end a roller 956. A groove cam 958 is fastened to the shaft 73 and its groove is engaged by the roller 956. An arm 959 with the forked end 960 has one end fastened to the shaft 85 953. A block 961 is located in the said forked end 960. The block 961 has an opening 962 the axial center of which is at various distances from its form side. The opening 967 engages the pin 292 of the slide 90 291. The axial center of the opening 962 is located as desired so that the block can be located on its different sides to take up lost motion when the opening 962 wears.

With the rotations of the shaft 73 shaft 95 953 is oscillated through the intervening elements. The arm 959 oscillates with the shaft 953 and thereby the slide 291 is reciprocated.

Referring to Figs. 1, 2, 7, 8 and 16 to 19 100 a pair of journal brackets 966 and 967 are fastened to the table 20 and have journaled thereon the shaft 968. Arms 969 and 970 have one end each fastened to the shaft 968. In the arm 970 is formed a longitudinal slot 105 971 through which extends a pin 972, that has supported thereon one end of the adjustable connecting rod 973. To the shaft 73 is fastened the grooved cam wheel 974. A journal bracket 975 is fastened to the 110 table 20 and has pivoted therein one end of an arm 976 by means of a pin 977. The end of the arm 976 is pinned to the connecting rod 973 by means of the pin 978. A roller 979 is journaled on the arm 976 and 115 engages the groove of the grooved car wheel 974.

The side frame 274 has formed therein a pair of vertical guides 985. A horizontal guide 986 has formed therewith the vertical 120 leg 987 having the elongated opening 988 for the clamping bolt 989 by which the leg 987 can be adjustably clamped to the frame 274.

To the upper end of arm 970 is pinned one 125 end of a link 990 by means of the pin 991, the other end of the link has pinned thereto a slide 992 by means of the pin 993. In

the side frame 275 there is located a vertical leg 994 with the horizontal guide 995, respectively similar to 987 and 986. The guide 995 has also slidably supported therein a 5 slide 996 similar to 992.

A link 997 has one end pinned to the arm 969 and the other end is pinned to the slide 996. Each of the slides 992 and 996 have extending therefrom a bracket 998 which 10 has formed therewith the stationary member 999 of a pin of grippers. A movable member for said grippers is indicated by 1000. An arm 1002 with the shoulder 1003 is formed with the member 1000. A boss 1004 is 15 formed with the movable member 1000. A hinge bolt 1005 is fastened to the member 1000 and extends through the boss 1004 and the bracket 998. A nut 1006 is in threaded engagement with the hinge bolt 1005 and 20 thereby the movable member 1000 is locked to the bracket 998. A spring 1007 is wound around the boss 1004 with one end of said spring bearing against the shoulder 1003 of the movable member 1000 and under the 25 stationary member 999.

With the horizontal guides 986, 995 is each fastened the split lug 1014 which carries a stop screw 1015. The latter is clamped in position on said lug by means 30 of the clamping screw 1016.

Pivot pins 1017 extend from the vertical side frames 350, 351 upon which are pivoted the latch tumblers with the arms 1018 and arms 1019. To the annular front frames 360 35 are fastened the lugs 1020 and each of the latter lugs carry an adjustable stop screw 1021. The latter are each in the path of the arms 1018.

With the rotations of the shaft 73 the 40 grooved cam wheel 974 oscillates the arm 976 through the intervention of the roller 979. By this means the connecting rod 973 swings the arm 970 and with the latter, through the intervention of the shaft 968 45 the arm 969 also swings. The arms 969 and 970 through the link 990 and link 997 reciprocates the slides 992 and 996. With each of these slides there is reciprocated the bracket 998, and thereby the grippers with 50 the stationary member 999 and movable member 1000 are also reciprocated.

When the latch ends 1001 during their movement in the direction of the arrow D strike the arms 1018, the grippers are opened 55 and are in position to grip the frame 136 with its duplex binder 141, 142. Upon slight further advance in the direction of arrow D the latch ends 1001 escape from the arms 1018 and thereby the said grippers are 60 closed upon and clamp the said frame 136 and duplex binder 141, 142. Upon the return stroke of the slides 992 and 996 the grippers carry the frame 136 and duplex binder 141, 142 to the lower face of the forming block 215 to be operated upon. When 65

this frame 136 and duplex binder 141, 142 has reached the forming block 215 the arm 1002 of the movable member 1000 of the grippers strikes the stop screw 1015, and the movable member 1000 of the grippers is 70 opened to release the frame 136 and its duplex binder 141, 142.

Simultaneously with the release of the frame 136 and the binder 141, 142 from the grippers having the member 1000, the said 75 frame and binder are supported upon the table 514 of the clamping and roller folding device 480.

Referring to Figs. 1, 2 and 32 to 35 attention is directed to the second clamping and 80 roller folding device 1025 of the apparatus. Upon the table 20 there is secured brackets 1030 and 1031. In the upper end of said brackets there is secured a sleeve guide 1032 with the leg 1033. Upon said sleeve is secured a bracket with the vertical jaws 1034 with the pivot pin 1035 and the horizontal jaws 1036 and 1037 with the pivot pins 1038 and 1039. On the pivot pin 1035 there is pivoted one end of the presser and guide arm 90 1042 having the guide opening 1043 with the curved end 1044. On the swinging end of said guide arm there is formed a cross bar 1045 which has openings for bolts 1046 that support the presser bar 1050. Springs 1051 95 bear between the cross bar 1045 and the presser bar 1050. A presser and guide arm 1052 having the guide opening 1053 with the curved end 1054 is pivoted in the leg 1033 by means of the pin 1055. On the swinging end 100 of the guide arm 1052 is formed a cross bar 1056 which has openings for bolts 1057, that support the presser bar 1061. Springs 1062 bear between the cross bar 1056 and the presser bar 1061. The enlarged portion 1069 105 to be explained has fastened thereto the disk 1063 with the separator 1064. To the latter is secured a spherical presser plate 1065. A rod 1065^a extends from the disk 1063 and engages an opening in the boss 1071. On the 110 sleeve guide 1032 there is slidably supported a sleeve 1066 which has a shouldered portion 1067. A plunger 1068 with the enlarged portion 1069 is slidably located in the sleeve 1066. A spring 1070 bears between the 115 shouldered portion 1067 and the enlarged portion 1069. The boss 1071 with the pairs of the jaws 1072, 1073, 1075 and 1076 is fastened to the enlarged portion 1069 of the plunger 1068. A pin 1077 passes through the guide opening 1043 and is fastened to the jaws 1072. A roller 1078 is supported upon the pin 1077. The jaws 1073 are connected by a pin 1079 which passes through the opening 1053 of the guide arm 1052. A roller 120 1080 is supported upon the pin 1079. On the pin 1088 there is pivoted a horizontal presser and guide arm 1081 and a roller guide arm 1082. The presser and guide arm has formed therewith a guide opening 1083 with 130

the curved end 1084. The cross bar 1085 is formed with the arm 1081 and has openings for the bolts 1086. The latter support the presser bar 1087. Springs 1088 surround 5 the bolts 1086, pass through the cross bar 1085 and are fastened to the presser bar 1087. The arm 1082 has formed thereon the guide opening 1092 and at the swinging end thereof has pivoted thereon a frame 1093 on 10 which latter is pivoted the folding roller 1096. A pin 1097 passes through the guide openings 1083, 1092 of both the arms 1081 and 1082 and is fastened to the jaws 1072.

A roller 1098 is supported upon the pin 1097. A pin 1099 extends from the arm 1081 and a pin 1100 extends from the arm 1082. A spring 1101 connects the pins 1099 and 1100. On the pin 1039 there is pivoted a horizontal presser and guide arm 1104 similar to 1081 and a roller and guide arm 1105 similar to 1082. The guide arm 1104 has formed therein a guide opening 1106 similar to 1083. A cross bar 1107 is formed with the arm 1104 and has openings for the bolts 1109. The latter support the presser bar 1110. Springs 1111 surround the bolt 1109, pass through the cross bar 1107 and are fastened to the presser bar 1110. The arm 1105 has formed therein the guide opening 1112 similar to 1092, and the swinging end thereof has pivoted thereon frame 1113 similar to 1093, in which latter is pivoted the folding roller 1115. A pin 1116 passes through the guide openings in both the arms 1104 and 35 1105 and is fastened to the jaws 1073. A roller 1117 is supported upon the pin 1116.

A pin 1118 extends from the arm 1105 and a pin 1119 extends from the arm 1104 and a spring 1120 connects the pins 1118 and 40 1119.

Upon the table 20 is bolted the journal bracket 1125 which is fastened in place by means of the screws 1126. An arm 1127 has one end fastened to a pin 1128 pivoted on the 45 journal bracket 1125. A roller 1129 is journaled on a pin 1130 extending from the arm 1127. A split bracket 1134 with the jaws 1135 is bolted to the sleeve 1066 and has pinned thereto one end of the link 1136 50 which in turn is pinned to the arm 1127. A grooved cam wheel 1137 is located between the upper portions of the brackets 1030 and 1031 and is fastened to the shaft 814. The wheel 1137 has a cam groove 1138 which engages the roller 1129.

The operations of the second clamping and roller folding device are as follows: When the operations on the box have been finished by the first clamping and roller folding device 480, the rotations of the shaft 73 cause the sector bevel gear 226, and the elements between the latter and the turret 160 to rotate the latter through an additional angle of 90 degrees. Thereby the forming block 215 which originally was opposite the box

head magazine is now opposite the second clamping and roller folding device that is supported on the brackets 1030 and 1031. With the rotations of shaft 814 and the cam wheel 1137, the arm 1127 is oscillated. This 70 reciprocates the sleeve 1066. The clamping and roller folding device which is now described is shown in its closed position but when the turret 160 locates the forming block 215 opposite thereto it will be in its 75 open position. To bring it to its open position the arm 1127 is swung in the direction of the arrow E, which causes the sleeve 1066 with the boss 1071 to move in the same direction. Thereby the rollers 1078 and 1080 80 enter the curved ends of the guide arms 1042 and 1052 and they respectively open. By this means the presser bars 1050 and 1061 separate from the box which is being manufactured. At the same time the rollers 85 1098 and 1117 by coacting respectively with their guide arm 1081, 1082, 1104 and 1105, the presser bars 1110 and 1087 separate from the sides of the box. The rollers 1096 and 1115 also swing away from said sides and at 90 the same time the plunger 1068, the spherical presser plate 1065 through the tension of the spring 1070 is separated from the box head 135 of the box that is being manufactured.

To cause the said second clamping and 95 roller folding device 1025 to perform its function the arm 1127 is swung in a direction opposite to that of the arrow E. Thereby the sleeve 1066 is moved in a direction opposite to that indicated by arrow E and 100 the arms 1042, 1052, 1081, 1082, 1104 and 1105 will be forced to their closed positions, as is particularly shown in Figs. 32 and 33. By this means the four sides of the box being manufactured will first be clamped by 105 the presser bars 1050, 1061, 1087 and 1110. Upon further movement of the sleeve 1066 the roller 1096 and 1115 hold over the vertical portions of the duplex binder upon the box head 125, and immediately thereafter 110 the spherical presser plate 1065 bears on said folded binder. Upon the further rotation of the turret 160 the box is discharged from the forming block 215 by reason of the latter entering its receptacle 182.

The various operations of the machine have already been described, as well as the different steps in the manufacture of the box as it is made. A recapitulation of the various stages of the box as it passes 115 through the different mechanisms will now be given for completeness.

Attention is called to Figs. 62 to 71 in conjunction with the appurtenances of the invention. The strip or member 142 is preferably made of paper of a color darker than that used for the strip or member 141 and which will be designated as the colored strip or member, and 141 as the white strip or member. The colored strip 142 is fed from 125 130

the reel 663 and by coming in contact with the drum 626 has one face thereof coated with glue. This member is ultimately led between the guide disks 611 which locate it 5 in proper alignment for its accompanying strip 141 of the duplex binder. The member 142 is then passed between the presser drum 597 and the presser wheel 583. The accompanying strip 141 led from the reel 10 664 passes over the drum 671 where one of its faces is coated with glue. The member 141 is led between the guide disks 610 which locates it in proper alignment for its accompanying member 142. The strip 141 is then 15 led between the presser drum 597 and presser wheel 83 where it is brought in contact with the member 142 to which it is glued by the pressure between said drum 597 and presser wheel 583. The duplex binder designated 20 by the two numerals 141 and 142 is then led over the pin 803 between the guide disks 804. The duplex binder then encounters the tension ring weight 805, which maintains the binder at the proper tension and 25 permits the binder to be pulled through the machine intermittently without being broken. The duplex binder next passes over the guide pin 787 and from the latter extends around the flanged guide roller 798. 30 The duplex binder then passes over the flanged roller 801, and from the latter over the flanged guide bosses 740 and 741, and by the operation of the grippers having the movable member 308 is pulled and located 35 upon the upper table 280. At the same time one of the frames 136, which has been prepared with the rectangular cross grooves 137, has been located upon said duplex binder by the means of the pusher having 40 the plates 726, 727 and their appurtenances. The shears with the long blades 879 and 894 now cut the duplex binder at one edge 143, the other edge 143 having been cut by the previous operation of said blades. At same 45 time a slit is cut in said duplex binder indicated by the edge 155. Said slit only partially extends through said binder. The box as far as manufactured is now supported as already stated upon the upper table 280. 50 Next the folding plate 334 performs its function and the member 142 of the duplex binder is folded upon the frame 136 as indicated in Fig. 62. The duplex binder and frame is now gripped by the grippers having 55 the movable member 308 and brought to the turret 160. While the above operations have taken place a box head 135 has been carried by said turret in proper position to be connected to said frame and binder 60 by means of the operations of the clamping roller and folding element 480, and by virtue of which the elements of the box take the form represented in Fig. 65. Next through the operation particularly of the 65 finger 425 and the latch 210 the binding

flap 144 is located in position as shown in Fig. 66. At the same time top and bottom portions of the member 142 of the binder with respect to their locations to the box head 135 has been folded over said box head 70 as indicated in Fig. 67. The box as far as complete is now carried by the turret 160 to the second roller folding and clamping device 1025 and the remaining portions of the member 142 of the binder is to the 75 head 135.

Having described my invention what I desire to secure by Letters Patent and claim is:

1. In a machine of the character described, 80 a turret comprising a turret head, means to rotate said head, receptacles connected to said head, a forming block having a cavity in one of its faces slidably supported in said receptacles, a latch coacting with said cavity, means to force said latch into said cavity and thereby fold a binder supported on said forming block.

2. In a machine of the character described, 90 the combination of a turret comprising a column, a sleeve encircling said column, a turret head formed with said sleeve, means to intermittently rotate the sleeve and its head, a groove disk encircling said sleeve and entering the turret head, a plurality of receptacles connected to the head, a forming block 95 slidably located in each receptacle, a plunger extending from each forming block through the turret head with its end over the groove disk, a roller journaled to said plunger and 100 engaging the groove of the groove disk, and means to oscillate the groove disk and thereby reciprocate the said plunger with the forming block.

3. In a machine of the character described, 105 a turret comprising a column, a sleeve with a turret head rotatably supported upon said column, a gear connected to said sleeve, means to intermittently rotate said gear, two pairs of locking blocks carried on said gear, 110 one pair at right angles to the other pair, a pair of arms pivoted in said machine, an adjusting arm pivoted to each of said arms, a locking foot for each of the adjusting arms and means to swing the first pair of arms to 115 lock the locking feet with said locking blocks after the turret head has been moved through an angle of ninety degrees.

4. In a machine of the character described, 120 the combination of a front plate with an upper table and a lower table, a folding frame to the rear of said front plate, a vertically reciprocating slide in the front of said front plate and connections between the said slide, front plate and folding frame 125 to cause the latter to be located from one of the tables of the front plate to the other table to fold a binder to a box frame located upon the upper table.

5. In a machine of the character described, 130

the combination of a front plate with an upper table and a lower table, a reciprocating slide for the front plate, a folding frame located to the rear of said front plate, means 5 between the folding frame and the reciprocating slide to vertically move the folding frame with the reciprocations of said slide and means to horizontally move the folding frame during its vertical movements.

10 6. In a machine of the character described the combination of a front plate with an upper table and a lower table, a reciprocating slide for the front plate, a cam moving with said slide, a pair of trippers pivoted to the 15 upper end of the front plate each with a pair of arms, one arm of each pair in the path of said cam, and swung by said arm when contacting therewith, a folding frame located to the rear of said front plate, a folding plate in the upper portion of said frame and in the path of each other arm of said pair of arms, the said plate being given a vertical movement when in contact with the latter arms, cam openings in the folding frame, guide openings in the folding frame, pivots moving with said slide engaging said cam openings and thereby laterally moving the folding frames, pivots moving with said slide engaging said guide openings to guide 20 the folding frame and a spring extending between the folding frame and the front plate to maintain said frame in proper operative position.

7. In a machine of the character described, 25 the combination of a front plate with an upper table and a lower table, the front plate having a central opening and an opening on each side of said central opening, a slide in front of said front plate, means to vertically reciprocate the slide, a pin fastened to the 30 slide and extending through the central opening of the front plate, a cam secured to the outer end of said pin, a pair of trippers pivoted to the upper end of the front plate, 35 each of the trippers having a pair of arms, one arm of each tripper in the path of said cam, a folding frame located to the rear of said front plate and comprising a folding plate at its upper portion, vertical members 40 each with a cam opening and a guide extending from the folding plate, a brace connecting the vertical members, a spring coacting with said brace and the said front plate, the said folding plate in the path of 45 the arms of the trippers, a pair of slotted pins extending from the slide and straddling said vertical members, a pivot in each of said pins engaging said cam openings, a pair of slotted pins extending from said front plate 50 and a pivot in each of the latter pins engaging said guide openings, the reciprocations of the slide forcing an arm of each of the trippers to separate thereby causing the said folding plate to rise and carry it from 55 the level of said lower table to the level of

said upper table, the coaction of the pivots with their cam openings laterally moving said folding plate so as to locate it upon the upper table.

8. In a machine of the character described 70 the combination of a head having a sleeve formed therewith, a spindle with a shouldered portion in said sleeve, a spring bearing between the upper end of the sleeve and said shouldered portion, an arm pivoted to said head and reciprocating therewith, a roller frame pivoted to said arm, a roller journaled in said frame and flexible means to laterally move the roller frame.

9. In a machine of the character described 80 the combination of a head having a sleeve formed therewith, a spindle flexibly connected to said sleeve, a guide plate extending from said head, a movable finger located in said guide plate, a spring connecting said 85 finger and the upper end of the guide in the guide plate and means to lock said finger in the guide plate.

10. In a machine of the character described 90 the combination of a head, means to reciprocate the head, a guide plate extending from the head, a spring actuated finger guided in the guide plate, a latch pin extending from the finger, a spring actuated spindle in said head, a clamping foot for the 95 spindle, a latch lever pivoted to said guide plate, one end of said latch lever located to engage said latch pin, a bracket to engage said latch pin, a bracket secured to the upper end of said spindle and a guide pin on said 100 bracket extending through an opening in said latch lever, the elements coacting with each other so that during the downward stroke of the head and when the clamping foot bottoms, the said spindle remains at 105 rest during the end of the downward stroke of said head, whereby the said guide pin coacting with the opening in the latch lever unlocks the latter from the pin extending from said finger and the finger is pulled up. 110

11. In a machine of the character described 115 the combination of a head, means to reciprocate said head, a guide plate extending from the head, a finger guided in the guide plate, a spring connecting the upper end of the finger and a shouldered portion of the guide plate, a spindle flexibly located in said head, a clamping foot for the lower end of the spindle, a latch lever pivoted at about its central portion to said guide plate, 120 one end of said latch lever located to engage a latch pin extending from said finger, a bracket secured to the upper end of said spindle and a guide pin carried on the said bracket and extending through an opening in said latch lever, the elements coacting with each other so that during the downward stroke of the head and when the clamping foot bottoms, the said spindle remains at rest during the end of the downward stroke of 125 130

said head, whereby the said guide pin coacting with the opening in the latch lever unlocks the latter from the pin extending from said finger and the spring coacting with 5 said finger pulls up the latter.

12. In a machine of the character described the combination of a turret head, a groove disk coacting therewith, a bracket with a pin extending from the groove disk, 10 an arm pivoted in the machine, means to oscillate the arm, a stem with a yoke slidably carried on the arm, a pair of guide screws carried on the yoke and a block with a pair of vertical grooves and an opening, 15 the said grooves engaged by the screw pins and the pin of the bracket extending through the opening of said block.

13. In a machine of the character described the combination of a pair of vertical 20 side frames, a front frame and a rear frame connected to the side frames, a shaft oscillating in bearings in the side frames, an arm with one end fastened to said shaft, a cross head in the path of the swinging end of 25 said arm, a sleeve extending from the front frame, a plunger with a spindle at one end and a clamping plate at the other end, the plunger fastened in the cross head and slidably supported in the rear frame, a spring 30 in the sleeve bearing against said plunger and a guide pin extending from the clamping plate and moving in an opening in the rear frame.

14. In a machine of the character described the combination of a box frame magazine comprising a pair of guide columns, a 35 reciprocating pusher under the said columns to discharge box frames therefrom, a vertical slide under one of the columns, a table 40 carried by the slide to support the binder of a box, a guide frame pivoted in the machine carrying a pair of guide arms, the said guide arms bearing on the table, means to intermittently lower the table and a guide 45 bracket fastened to one of the guide columns extending between the said guide arms in proximity to the table.

15. In a machine of the character described the combination of a box frame magazine, a slide for the magazine, a table carried by the slide to support box frames as 50 they are discharged therefrom and also to support a binder for the box frames, a spring to maintain the table in its normal position, a bracket extending from the slide, a reciprocating link in the machine and a trigger carried on the link in the path of 55 said bracket to intermittently lower the slide with the table.

16. In a machine of the character described the combination of a box frame magazine comprising a pair of guide columns, a reciprocating pusher under the said columns to discharge box frames therefrom, a verti- 60

cal slide for the magazine, a table carried by 65 the slide to support the binder of a box, a guide frame pivoted in the machine carrying a pair of guide arms, the said guide arms bearing on the table, a guide bracket fastened to one of the columns extending between the said guide arms in proximity to the table, a bracket extending from the slide, a reciprocating link in the machine and a trigger carried on the link, said trigger in the path of the bracket extending from the 75 slide to intermittently lower the latter.

17. In a machine of the character described a clamping roller and folding device comprising a reciprocating sleeve, a bracket carried by the sleeve, a plunger in the sleeve, 80 a bracket carried by the plunger, guide arms with guide openings pivoted to the latter bracket, a pair of pins extending from the first bracket and extending through guide openings in the guide arms, a binding and 85 clamping finger pivoted to each guide arm, connections between each finger and one of said pins, a bending and clamping bar flexibly supported on each guide arm and a folding roller flexibly connected with the first 90 bracket.

18. In a machine of the character described, a clamping roller and folding device comprising a reciprocating sleeve, a bracket with an apron and vertical members 95 carried by said sleeve, a spring controlled plunger in the sleeve, a bracket carried by the plunger, guide arms with guide openings pivoted to the latter bracket, a pin extending from each vertical member and passing 100 through the guide openings of the guide arms, a bending and clamping finger pivoted to each guide arm, a spring controlled plunger pivoted to each finger, a barrel coacting with each plunger pivoted on the pin extending from its coacting vertical member, a bending and clamping bar flexibly supported on each guide arm, an arm with one end pivoted to said apron, flexible means to maintain the latter arm in operative position 110 and a folding roller journaled at the upper end of the latter arm.

19. In a clamping roller and folding device the combination of a reciprocating sleeve, a spring controlled plunger in said 115 sleeve, a presser plate for the plunger, vertical presser and guide arms pivoted above said plunger, a vertical presser and guide arm pivoted below said plunger, a horizontal presser and guide arm pivoted on one 120 side of said plunger, a second horizontal presser and guide arm pivoted on the opposite side of said plunger, a roller and guide arm pivoted with each horizontal presser and guide arm, a presser bar flexibly supported on each presser and guide arm, a folding roller for each roller and guide arm, four pairs of jaws extending from said 125

sleeve, the presser and guide arms pivoted to the jaws and means to reciprocate the sleeve.

20. In a machine of the character described a clamping roller and folding device comprising a reciprocating sleeve, a spring controlled plunger in said sleeve, a presser plate for the plunger, a pair of vertical and a pair of horizontal presser bars in 10 the device, means to move said bars and a folding roller coacting with each horizontal presser bar.

21. In a clamping roller and folding device the combination of a sleeve guide, a 15 sleeve slidably supported in said sleeve guide, a spring controlled plunger in said sleeve, a presser plate for the plunger, vertical presser and guide arms pivoted above said plunger, a vertical presser and guide 20 arm pivoted below said plunger, a horizontal presser and guide arm pivoted on one side of said plunger, a second horizontal presser and guide arm pivoted on the opposite side of said plunger, a roller and guide arm pivoted with each horizontal presser and guide arm, a presser bar flexibly supported on each presser and guide arm, a frame pivoted in each roller and guide arm, a folding roller pivoted in each of said frames, a 25 boss with four pairs of jaws fastened to one end of said sleeve, a pin with a roller for each pair of jaws, two pairs of said rollers engaging the vertical presser and guide arms and two pairs of said rollers engaging the horizontal 30 presser and guide arms, and means to reciprocate the sleeve.

22. In a machine of the character described, a clamping roller and folding de-

vice comprising a pair of brackets, a sleeve guide supported on the brackets, a sleeve 40 slidably supported in said sleeve guide, a spring controlled plunger in said sleeve, a presser plate for the plunger, a vertical presser and guide arm pivoted above said plunger, a vertical presser and guide arm 45 pivoted below said plunger, a horizontal presser and guide arm pivoted on one side of said plunger, a second horizontal presser and guide arm pivoted on the opposite side of said plunger, a roller and guide arm 50 pivoted with each horizontal presser and guide arm, a presser bar flexibly supported on each presser and guide arm, a frame pivoted in each roller and guide arm, a folding roller pivoted in each of said frames, a 55 boss with four pairs of jaws fastened to one end of said sleeve, a pin with a roller for each pair of jaws, two pairs of said rollers engaging the vertical presser and guide arms and two pairs of said rollers engaging 60 the horizontal presser and guide arms and the roller and guide arms, a bracket fastened to the sleeve, a link with one end pinned to said bracket, an oscillating arm in the machine with one end pinned to the other end 65 of said link, the oscillations of the arm causing the movement of all the elements of the device.

Signed at the borough of Manhattan, in the county of New York and State of New York, this 22nd day of October A. D. 1915. 70

ZYGMUNT LIPOWSKI.
